SLICED BACON PACKAGE

Robert M. Dunning, St. Paul, Minn., assignor to Waldorf Paper Products Company, a corporation of Minnesota

Filed May 10, 1956, Ser. No. 584,100

5 Claims. (Cl. 229—87)

This invention relates to an improvement in packages and deals particularly with a package useful in containing sliced bacon or a similar product.

Various types of packages have been produced for containing a measured amount of sliced bacon. The bacon is usually placed in these packages with the longitudinal edges of the strips in overlapping relation so that the strips are in-stepped relation. As a result of this arrangement, the longitudinal edges of the package may be thinner than the remainder of the package as the ends strips of the series are not built up in thickness by superimposed layers of bacon. Thus it is the purpose of the present invention to provide a package where the longitudinal edges are thinner than the central portions of the package.

It has been found that by providing a package or folder having end walls which taper in thickness toward their juncture with the sides of the package, the desired result may be obtained. Such an arrangement is provided by forming the end walls with substantially parallel fold lines throughout the major portion of their length and by providing converging fold lines connecting the ends of these fold lines with the juncture between the end walls and the sides of the package. As a result a package is provided which is relatively thin or which may have no side walls along the longitudinal edges of the package and yet which is relatively thick throughout the central part of the package.

A further feature of the preferred form of construction of the invention resides in the provision of a package having substantially flat upper and lower surfaces and having tapering edge portions which taper in thickness to the marginal longitudinal edges of the package. As a result, the packages may be placed one upon the other and will stack effectively for storage or for display but at the same time the package is provided with the proper cross-sectional shape.

These and other objects and novel features of the present invention will be more clearly and fully set forth in the following specification and claims.

In the drawings forming a part of the specification:

Figure 1 is a perspective view of a bacon package showing the new construction.

Figure 2 is a top plan view of the package illustrated in Figure 1.

Figure 3 is an elevational view of the package shown in Figures 1 and 2.

Figure 4 is a diagrammatic view of the blank from which the package is formed.

Figure 5 is a diagrammatic view of a slightly different form of blank from that illustrated in Figure 4.

Figure 6 is a perspective view of a modified form of package in which the bacon is entirely enclosed.

Figure 7 is a plan view of the package shown in Figure 6 after the package has been sealed.

Figure 8 is a diagrammatic view of the blank from which the package of Figures 6 and 7 is formed.

Bacon packages may be of several types. Some such

2

packages include a bottom panel, a pair of end panels which fold over the bottom panel to overlie the ends of the strips of bacon, and a side or bottom panel which folds to overlie one or more of the end strips of the series. In this arrangement, only the overlapped marginal edges of the bacon strips are visible when the package is closed. Others prefer to use a slightly more expensive package construction which entirely encloses the bacon strips. This type of package may be provided with a window through which portions of the overlapped strips are visible if it is so desired. The present invention is designed to form either of these types of packages, it being only necessary to modify the shape and form of the various closing flaps to accomplish either results.

15 In the form of construction illustrated in Figures 1 to 4 of the drawings, the bottom panel 10 is foldably connected along a fold line 11 to a cover flap or panel 12. The ends of the bottom panel 10 are foldably connected to end wall panels 13 and 14. The fold lines connecting the bottom panel to the end wall panels is not a straight fold line. In the arrangement illustrated in Figure 4 of the drawings, the fold lines connecting the bottom panel to the end wall panels include parallel fold lines 15 and 16 respectively which extend the major part of the distance between the free edge 17 of the bottom panel 10 and the folded edge 11 thereof. An angularly inclined fold line 19 extends from one end of the fold line 15 to the free edge 17 and a similarly inclined fold line 20 forms an extension of the fold line 15 and extending to the juncture between the bottom panel 10 and the fold line 11.

20 The fold line 16 also extends the major portion of the width of the bottom panel 10 and one end of this fold line is provided with an angular continuation 22 which extends to the free edge 17 of the panel 10 and includes an angular extension 23 which extends from the fold line 16 to the juncture between the panel 10 and the cover panel 12.

25 The end wall 13 is defined by a fold line 24 which extends parallel to and spaced from the fold line 15. The fold line 24 is coextensive with the fold line 15 and the ends of this fold line 24 are connected by angularly inclined extensions 25 and 26 to the outer ends of the fold line extensions 19 and 20. In other words the fold lines 19 and 25 diverge apart from the marginal edge 17 of the bottom panel to the spaced fold lines 15 and 24. Similarly the fold lines 20 and 26 diverge apart from the fold line 11 to the ends of the fold lines 15 and 24. In other words in this form of construction, the end wall 13 is generally hexagonal in shape.

30 The end wall 14 is shaped similarly to the end wall 13. The end wall 14 is connected by a fold line 27 to the top cover flap or panel 29. The fold line 27 is parallel to the fold line 16 and coextensive therewith. The ends of the fold line 27 are connected by angularly inclined extensions 30 and 31 to the panel edge 17 and the panel edge 11 respectively. Thus the end wall 14 is generally hexagonal in shape although the length of the end walls are much greater than the height thereof.

35 The fold line 24 with its extensions 25 and 26 foldably connects the end wall 13 to a top cover flap or panel 32. Both the top panel 32 and the top panel 29 are provided with locking slits 33 and 34 respectively by means of which the top cover flaps or panels 32 and 29 may be connected to the cover panel 12.

40 When the package "A" is used the strips of bacon are placed upon the bottom panel 10 with the longitudinal edges in overlapping relation and with the ends of the strips between the fold lines 15 and 16. The panel or flap 12 is then folded about its fold line 11 so as to overlie one or more of the overlapped strips of bacon. This flap thus normally conceals the major portion of the last

strip of bacon of the series which would otherwise be exposed in its entirety. The end walls 13 and 14 are then bent upwardly in right angular relation to the bottom panel 10. This action causes the bottom panel 10 to flex upwardly near the edges 17 and 11 of the bottom panel to follow the confirmation of the fold line 15 and its extensions 19 and 20.

The top flaps 32 and 29 are the next folded downwardly to overlie the ends of the strips of bacon. During this folding operation, the ends of the flaps 32 and 29 which are in alignment with the edges 17 and 11 of the bottom panel 10 also flex downwardly to follow the confirmation of the fold line 24 and its extensions 25 and 26 and the confirmation of the fold line 27 and its extensions 30 and 31. As a result, when viewed from the end, the package is generally hexagonal in shape.

Because of the irregular width of the end panels 13 and 14, the resulting folded package is longer along its longitudinal edges than through the center portion of the package. In other words, the end walls 13 and 14 also flex from the ends of the parallel fold line portions to the point where the fold line extensions converge together. As a result the package is not entirely rectangular in plan after it has been folded. However, the package may be overwrapped with a rectangular sheet of transparent material such as 35 as the increase in length along the longitudinal edges of the packages compensates for the increase in height of the end walls of the shorter intermediate portion of the package. During the folding of the top flaps 32 and 29, the locking cuts 33 and 34 are engaged with the marginal edge of the panel 12 to hold the folder in close position prior to the overwrapping operation. Actually, the overwrapping of the package is optional but is usually done to protect the carton contents. Alternatively, a covering sheet may be adhered to the bottom panel 10 and to project therefrom in a direction opposite the projection of the panel 12 and this covering sheet may be folded to overlie the bacon before the various flaps are folded into covering position.

In Figure 5 of the drawings I disclosed a slightly modified form of construction which does not have many of the advantages described in conjunction with the package "A" but which forms a package of unusual appearance. The package "B" illustrated in Figure 5 of the drawings includes a bottom panel 36 which is foldably connected along one longitudinal edge by a fold line 37 to a cover or side panel 39. The ends of the bottom panel 36 are connected along arcuate fold lines 40 and 41 to end walls 42 and 43 respectively. The center of arcuation of the fold lines 40 and 41 is externally of the bottom panel 36 so that the ends of the bottom panel are concave.

The end walls 42 and 43 are connected along second arcuate fold lines 44 and 45 to cover panels 46 and 47 respectively. The fold lines 44 and 45 are arcuate in a direction opposite to the arcuation of the fold lines 40 and 41 so that the end walls 42 and 43 are relatively thick at a point midway between the free edge 49 of the bottom panel and the fold line 37. These end walls 42 and 43 taper to a minimum height at the ends so that the fold lines converge together at each end of the end walls.

This arrangement has the disadvantage that when the package is folded, the bottom panel 36 as well as the top panels 46 and 47 are bowed downwardly and upwardly respectively resulting in a package which is continuously rounded from one edge to the other. As a result of this arrangement, the packages will not stack effectively and therefore packages of this type are not entirely the equivalent of the package "A."

In Figures 6, 7, 8, of the drawings I disclosed a modified form of package, this package being indicated in general by the letter "C." As is indicated in Figure 8 of the drawings, the blank from which the package "C"

is made is generally rectangular in form. It includes a bottom panel 50 which is foldably connected along its longitudinal edges by fold lines 51 and 52 to generally triangular closing flaps 53 and 54 respectively. The ends 5 of the bottom panel 50 are foldably connected to end walls 55 and 56 by parallel fold lines 57 and 59 which extend the major portion of the width of the bottom panel and are provided with angularly inclined extensions connecting the ends of these fold lines to the side edges of the bottom panel. Fold line extensions 60 and 61 connect the ends of the fold line 57 with the sides 51 and 52 of the bottom panel 50 while similar fold line extensions 62 and 63 connect the ends of the fold line 59 with the bottom panel edges 51 and 52. The various fold line extensions incline outwardly from the center 10 of the bottom panel 51 so that the fold lines 57 and 59 are closer together than are the ends of the fold line extensions.

The end walls 55 and 56 are foldably connected to 20 closing flaps 64 and 65 which are generally triangular in shape. The fold lines connecting the end walls to the flaps 64 and 65 include parallel fold line portions 66 and 67 which are connected by fold line extensions to the side edges of the bottom panel 50. Fold line extensions 69 and 70 connect the ends of the fold line 66 to a junction with the fold lines 51 and 52 while fold line extensions 71 and 72 connect the ends of the fold line 67 to a junction with the fold lines 51 and 52. As a result of 25 this arrangement, the end walls 55 and 56 are generally 30 hexagonal in shape and the ends of end walls are of relatively no height while the main portions of these end walls are of sufficient height to contain the strips of bacon within the closed package.

As is indicated in the drawings, the triangular flaps 53 35 and 54 are connected to the fold line 51 by generally parallel end edges 73 and the closing flaps 64 and 65 are also connected to the ends of the side walls 55 and 56 by generally parallel end portions 74. This arrangement is provided so that the various flaps will overlap when 40 folded into position to enclose the folder contents.

In the particular arrangement illustrated, a window opening 75 is cut in the center of the bottom panel 50 and a generally rectangular transparent sheet 76 is adhered to the bottom panel 50 particularly around the window 45 opening 70 as by the adhesive 77. If no package lining is required, the transparent covering 76 may extend only over the window opening 75 to slightly overlap the marginal edges of the bottom panel. However, if a package 50 liner is desired, the transparent sheet 76 is practically co-extensive with the blank from which the package is formed, the liner folding inwardly with the various closing flaps.

In operation, the strips of bacon or similar material are placed upon the bottom panel 50 between the fold lines 55 57 and 59, and the end walls 55 and 56 are folded upwardly into right angular relation with the bottom panel. This folding causes the longitudinal edges of the bottom panel to fold upwardly to some extent to follow the contour of the fold line extensions 60 and 61 at one end 60 of the package and the fold lines 62 and 63 at the other end thereof. The flaps 64 and 65 are then folded to overlie the package contents, these flaps being flexed out of a common plane due to the angular inclination of the fold lines 69 and 70 at one end of the package and the fold 65 line extensions 71 and 72 at the opposite end thereof. The closing flaps 53 and 54 are then folded to overlie the first folded flaps. Any convenient means is provided for sealing the flaps in closed position, Figure 7 illustrating a pair of short lengths of pressure sensitive tape 80 for this purpose. These short lengths of tape overlie the junctures between certain of the flaps and seal the package in closed 70 position.

It will be seen that the package "C" when folded as indicated in Figures 6 and 7 of the drawings, has an end 75 elevation similar to that of the package "A" and similar

to that shown in Figure 3 of the drawings. When the folded package is viewed in plan as in Figure 7 of the drawings, they will be seen that the central portions of the end walls which are defined by the parallel fold lines are somewhat closer together than the ends of the end walls, the end walls flexing outwardly so that the longitudinal edges of the package are longer than the center portion thereof. The package thus formed is accordingly distinctive in appearance as it is of unusual shape. At the same time, however, the top and bottom surfaces of the package are parallel so that the packages will stack readily and will rest flat one upon the other when placed in a shipping container or placed on display.

In accordance with the patent statutes, I have described the principles of construction and operation of my package and while I have endeavored to set forth the best embodiment thereof, I desire to have it understood that obvious changes may be made within the scope of the following claims without departing from the spirit of my invention.

I claim:

1. A carton including a paperboard sheet cut and creased to provide a base panel having opposed parallel edges, relatively narrow end walls foldably connected to the remaining edges of said base panel, and top panels hingedly connected to said end walls, said end walls being generally hexagonal in shape and defined by parallel lines of fold at right angles to said parallel edges and extending the major portion of the distance between said parallel edges, and relatively short converging fold lines connecting the ends of said parallel fold lines and said parallel edges, the base panel being connected to the end walls along three adjoining edges of said hexagonal end walls, and the top panels being foldably connected to the remaining three edges of said hexagonal end walls the major portions of the end walls between said parallel fold lines being in parallel relation and at substantially right angles to said base panel, the major portions of said top panels and said base panel between the parallel portions of said end walls being substantially flat and parallel, the edge portions of said base panel and top panels connected to said converging fold lines being flexed into converging relation.

2. The structure of claim 1 and including an additional top panel foldably connected to one of said parallel edges of said base panel.

3. The structure of claim 1 and including a top panel foldably connected to each of said parallel edges of said base panel.

4. A carton including a paperboard sheet cut and creased to provide a base panel having opposed parallel edges, relatively narrow end walls foldably connected to the remaining edges of said base panel, and top panels hingedly connected to said end walls, said end walls being

- generally hexagonal in shape and defined by parallel lines of fold at right angles to said parallel edges and extending the major portion of the distance between said parallel edges, and relatively short converging fold lines connecting the ends of said parallel fold lines and said parallel edges, the base panel being connected to the end walls along three adjoining edges of said hexagonal end walls, and the top panels being foldably connected to the remaining three edges of said hexagonal end walls, the major portions of the end walls between said parallel fold lines being in parallel relation and at substantially right angles to said base panel, the end portions of said end walls between said converging fold lines angling outwardly beyond said parallel portions of said end walls, the major portions of said top panels and said base panel between the parallel portions of said end walls being substantially flat and parallel, the edge portions of said base panel and top panels connected to said converging fold lines being flexed into converging relation.
5. A carton folder including a base panel of generally rectangular outline having opposed parallel edges, a narrow end wall foldably connected to a third edge of said base panel, said end wall being generally hexagonal in outline and being defined by parallel fold lines extending at right angles to said parallel edges across the major portion of the distance between said parallel edges and terminating short of the parallel edges, and by converging fold lines extending from the ends of the parallel fold lines to the parallel edges of the base panel, said base panel being connected to said hexagonal end wall along one of said parallel fold lines and the two adjoining of said converging fold lines, a top panel foldably connected to said end wall along the remaining of said fold lines, said end wall holding the major portions of said base panel and top panel parallel when these panels are in right angular relation to said end wall.
